UNITED STATES PATENT OFFICE.

WILLIAM A. SWIM, OF ALMENA, KANSAS.

FENCE-POST.

1,076,328.

Specification of Letters Patent. Patented Oct. 21, 1913.

Application filed August 31, 1912. Serial No. 718,070.

To all whom it may concern:

Be it known that I, WILLIAM A. SWIM, a citizen of the United States, residing at Almena, in the county of Norton and State of Kansas, have invented new and useful Improvements in Fence-Posts, of which the following is a specification.

An object of the invention is to provide a post comprising a plurality of parts, one of which constitutes a supporting member for supporting the wires of the fence, and the other of which constitutes a locking member for securing the wires in locked and supporting position on the first or supporting member.

In the further disclosure of the invention reference is to be had to the accompanying drawings, constituting a part of this specification, in which similar characters of reference denote corresponding parts in all the views, and in which:

Figure 1 is a fragmentary perspective view of a fence showing the wires thereof supported by my fence post; Fig. 2 is a vertical sectional view taken on the line 2—2 in Fig. 1; Fig. 3 is a horizontal transverse sectional view taken on the line 3—3 in Fig. 1; and Fig. 4 is a perspective view of the locking member; Fig. 5 is a horizontal sectional view taken on the line 5—5 in Fig. 2.

Referring more particularly to the views, use is made of an upright 10 preferably formed of metal of a U-shape in cross section, the said upright having a base 11 for insertion in the ground or in concrete and provided above the base with a series of horizontally arranged slots 12 adapted to receive therein wires 13 of a fence 14, thus retaining the wires 13 in spaced relation as shown in Fig. 1.

A locking member 15 is provided for the upright 10, the said locking member being preferably made of metal of a U-shape in cross section, the said locking member being provided with a longitudinally extending slot 16, forming curved flanges 17 adapted to engage the wires 13 and secure the same within the slots 12 when the locking member 15 is mounted on the upright 10 by being placed within the upright as shown in Fig. 1. Stop lugs 18 are formed on the lower end of the locking member 15 and are adapted to engage the base 11 of the

upright 10 for the purpose of preventing the locking member 15 from sliding downwardly on the upright, a securing pin 19 being preferably passed transversely through the upper portion of the upright 10 and the upper portion of the locking member 15 to rigidly lock the locking member on the upright, the said locking member having a lip 20 formed at the lower end thereof and adjacent to the stop lugs 18, the said lip being adapted to extend into the base 11 of the upright 10, the mentioned base 11 being preferably of a tubular nature in order that when the locking member 15 is mounted on the upright 10 the lip 20 will readily extend into the tubular base so that after the pin 19 is mounted in place the accidental removal of the locking member 15 will be prevented.

It will be noted that after the wires 13 of the fence 14 are arranged in the slots 12 of the upright 10 and the locking member 15 is placed in position on the upright, the pressure exerted by the flanges 17 of the locking member 15 against the wires 13 will tend to bend the wires between the slots 12 of the upright, thus producing a tension on the wires so that the same will not sag and will lie in substantially horizontal lines.

Having thus described my invention, I claim:

As a new article of manufacture, a fence post comprising a U-shaped upright having a tubular base for insertion in the ground and having an upper portion of the upright provided with a series of horizontally arranged slots adapted to receive wires therein and support the same in spaced relation on the upright, a locking member, U-shaped in cross section and having a medially arranged longitudinally extending slot and curved longitudinal parallel flanges, spaced apart and constituting the walls of the said slot, with the said flanges engaging the wires on the upright to secure the same in the inner ends of the slots and wholly within the slots so that the said wires will lie beyond the vertical plane of the upright when the locking member is engaged therewith, and spaced integral stop lugs formed on the lower end of the locking member by cutting away the edges thereof, with the said stop lugs engaging the tubular base to support the locking member on the upright,

a pin passing transversely through the upper end of the upright and the locking member, and a lip formed on the lower end of the locking member by the cut away portions thereof, with the said lip projecting downwardly beyond the stop lugs and into the tubular base of the upright.

In testimony whereof I affix my signature in presence of two witnesses.

WILLIAM A. SWIM.
